MACHINE FOR SHAPING SHOE UPPERS

Arthur Bates, Leicester, England, assignor to
 United Shoe Machinery Corporation, Paterson,
 N. J., a corporation of New Jersey

Application September 11, 1933, Serial No. 688,885
 In Great Britain October 22, 1932

87 Claims. (Cl. 12—4)

This invention relates to machines for operating on shoe uppers to impart to each upper, or to a portion thereof, the shape that it is to have in the finished shoe. In prior United States Letters Patent No. 1,897,037, granted on February 14, 1933 upon an application of mine, there was disclosed a machine constructed to operate upon a previously untensioned upper to tension it over a last and to work the forepart of the upper into lasted relation to the last and to an insole on the last. Among its objects, the present invention has particularly in view certain improvements in a machine organization of the general character there disclosed, and it is accordingly herein illustrated as applied to such an organization; but it is to be understood that in various novel aspects the invention is not thus limited in its applicability.

In one aspect, the invention provides novel means for applying a binder to an upper around an end of a shoe to hold the upper in lasted position. In the illustrative machine the marginal portion of the upper around the toe is wiped into lasted position against a lip on the insole by toe-embracing wipers; and for the purpose in view the construction herein shown comprises grippers that grip a wire binder at the opposite sides of the shoe and are moved relatively to the wipers, in response to the operative movement of the wipers, to pull the binder tightly against the margin of the upper. As further herein illustrated, the wipers are provided at their wiping edges with a groove to receive the binder, and prior to the operation of the machine the operator places the binder in this groove and in the above-mentioned grippers which are located beyond the rear ends of the wipers.

Further novel features of the invention are to be recognized in the combination of binder-applying means and means for fastening the binder to the shoe, and also in details of the fastening means. As herein illustrated, the binder is fastened by staples driven in notches located at the wiping edges of the wipers, but it is to be understood that the invention is not limited to the use of staples nor to means for driving the fastenings in that relation to the wipers. In the construction shown, similarly to the disclosure of the above-mentioned Letters Patent, the wipers are extended lengthwise of the shoe to wipe the upper into lasted position substantially as far rearwardly as the ball line of the shoe; and to fasten the binder there are driven at each side of the shoe bottom a pair of staples located respectively near the toe tip line and at the ball

of the shoe. For greater security in the holding of the binder, the invention provides means for driving staples the legs of which diverge from each other toward their work-penetrating ends and are spaced from each other near their cross-bars by distances less than the diameter of the binder to cause them to clamp the binder between them as they are driven; and in this aspect of the invention a novel method also is to be recognized. The fastenings are driven, in the illustrative machine, from guides that are movable relatively to the wipers both heightwise and laterally of the shoe into fastening-inserting positions; and in accordance with a further feature of the invention these guides are so constructed and operated that they press the binder against the upper prior to the driving of the fastenings. In accordance with still other features novel means are provided for operating and controlling the guides for the fastenings and for operating and controlling the drivers that drive the fastenings.

The machine disclosed in the above-mentioned Letters Patent included grippers arranged to grip the marginal portion of the upper outspread at the opposite sides of the toe and movable inwardly toward the last in response to the pull of the upper thereon in the upper-shaping operation. The present invention provides additional grippers for similarly controlling the upper farther rearwardly than the toe portion, these grippers in the construction shown being arranged to grip the upper in locations slightly nearer the toe than the ball line. A feature of the invention also is to be recognized in novel details of construction of these grippers and of their operating and controlling means.

The above and other features of the invention, including also novel means for clamping the upper about the forepart and novel means for positioning the upper relatively to the upper-shaping means, will now be more particularly described by reference to the accompanying drawings and pointed out in the claims.

In the drawings,
 Fig. 1 is a view in right-hand side elevation of a portion of a machine in which the invention is embodied;

Fig. 2 is a view in front elevation of the portion of the machine shown in Fig. 1;

Fig. 3 is a front view on a larger scale than Fig. 2, showing in greater detail the staple-inserting mechanism which appears at the right-hand side of Fig. 2;

Fig. 4 is a plan view of a portion of the ma-

chine, with parts broken away, showing the relation of certain parts to one another prior to the operation of the machine on a shoe;

Fig. 5 is a view similar to Fig. 4, but showing the shoe and illustrating the positions of the parts at the time when the wipers have substantially completed their overwiping movements;

Fig. 6 shows one of the staple-inserting devices in side elevation;

10 Fig. 7 is a sectional view of a portion of the shoe, with the lower end of one of the staple-guiding tubes shown in dotted lines, illustrating the manner in which the staples are driven into the work;

15 Fig. 8 is a perspective view showing the relation between one of the wipers and means provided for gripping the binder wire;

20 Fig. 9 shows in front elevation one of the mechanisms for gripping the upper at or near the ball of the shoe; and

Fig. 10 is a perspective view of a portion of the means provided for positioning the upper in proper relation to the machine.

Similarly to the disclosure of the above-mentioned Letters Patent, the machine in which the invention is herein illustrated as embodied comprises two sets of operating instrumentalities arranged side by side on a common base 1 for operating respectively on right and left shoes. For an understanding of the invention, however, it is necessary to refer only to one of these sets of instrumentalities, and accordingly portions only of that set which is located at the right-hand side of the machine are herein shown and will be described in detail.

In general similarity to the disclosure of the above-mentioned Letters Patent, there are provided, for supporting the last in the course of the operation of the machine and for pressing the upper against portions of the last, two inflatable pads 3 which engage the upper underneath and along the sides of the last at the rear of the toe portion and a pad 5 which engages the upper under the toe end of the last, the several pads being mounted on a support 6 that is movable downwardly against the resistance of a spring (not shown). For depressing the last and forcing it into the upper there is provided a downwardly swinging arm 7 which carries a block 9 pivoted at 11 on the arm to permit relative movement between it and the arm in response to resistance of the support 6 and its spring to downward movement of the last so as to impart to the last a lengthwise upper-stretching movement, as fully disclosed in said Letters Patent. The block 9 carries a toe plate 13 (Fig. 2) arranged to engage the toe end of the insole on the last and a presser foot 15 arranged to engage the insole at the waist portion of the shoe. Similarly also to one form 60 of construction disclosed in the earlier Letters Patent, the block 9 carries a toe-end abutment 17 arranged to engage the toe-end face of the last to assist in imparting to the last its lengthwise movement. In general similarity likewise to the earlier machine, there are provided clamp members 18 which clamp the marginal portion of the toe end of the upper outspread upon toe-embracing wipers 21 so as to tension the upper over the last both lengthwise and heightwise thereof in response to the movement of the last, and grippers 19 (Figs. 2 and 3) which grip the margin of the upper outspread over the wipers near the ends of the tip line to assist in tensioning the upper, these grippers being mounted for inward swinging movements toward the last against

spring resistance about pivots 25 extending lengthwise of the last and supported on brackets 27 that are secured to the head of the machine near the front of the latter. In the construction herein shown, as more particularly hereinafter described, there are further provided two additional grippers 23 arranged to grip the margin of the upper at or near the ball of the shoe, these grippers being utilized in place of the members 114 shown in the previously mentioned Letters Patent as arranged to clamp portions of the margin of the upper upon the wipers.

In the construction herein shown, for purposes of the present invention, there are two swinging brackets 29, one at each side of the shoe, which serve as carriers for staple-inserting mechanisms hereinafter described, each of these brackets being mounted to swing downwardly and inwardly about a pivot 31 extending lengthwise of the shoe and secured to the front face of the bracket 27, the pivot being located near the upper end of the bracket and at the inner side thereof, i. e., the side which is nearer the shoe. Each of the swinging brackets 29 has mounted in it at its outer side a rotatable pin 33 extending lengthwise of the shoe, and on this pin is pivotally mounted a short depending link 35 connected at its lower end to the upper end of a vertical rack bar 37 slidable vertically in a fixed guide-way 39 in the bracket 27. Each rack bar 37 is engaged at its lower end by a pinion 41 (Fig. 1) which also meshes with a horizontal rack bar 43 extending lengthwise of the shoe. The two horizontal rack bars 43 are connected together by pinions 45 secured to the opposite ends of a rotatable shaft 47 mounted in fixed bearings and extending laterally of the shoe, so that movement of one rack bar 43 causes a similar movement in the same direction to be imparted to the other rack bar. One of the rack bars 43 is connected at its rear end by a link 49 to the upper end of a cam-operated lever (not shown). By the operation of this lever accordingly swinging movements are imparted to the two opposite brackets 29, the lower end portions of which are thus swung toward and from each other as well as downwardly and upwardly.

The above-mentioned rotatable pin 33 in each of the swinging brackets 29 has freely pivoted on it a pair of short inwardly extending arms 51 which are pivotally connected at their inner ends, by pivot pins 53 extending lengthwise of the shoe, to the upper ends of a pair of staple and driver-guiding tubes 55. These tubes are spaced apart lengthwise of the shoe and extend downwardly and rearwardly (i. e., away from the front of the machine) at an angle of about 10° to the vertical (Fig. 1). The tubes 55 have formed on them at their front and rear sides flat guiding faces 57 (Figs. 3 and 6) which are received between guiding faces provided on inwardly extending lower portions 59 of the swinging bracket 29. Substantially horizontal springs 61 (one of which is shown in Fig. 3) extending laterally of the machine are connected at their inner ends to the lower portions of the tubes 55 and at their outer ends to hooks fixed in the bracket 29, the springs thus serving to urge the tubes outwardly along the guiding faces on the bracket until they abut against adjustable stop screws 63 threaded substantially horizontally into the portions 59 of the bracket. A pair of upwardly extending rods 65 lying one behind the other, one for each of the previously mentioned inwardly extending arms 51, are pivoted at their lower ends to pins 67 on

the swinging bracket 29 below the arms 51 and extend upwardly through trunnion bearings 69 mounted on the sides of the arms 51. Compression springs 71 are located between the upper 5 sides of these trunnion bearings and nuts 73 on the upper ends of the rods 68 and serve to urge the arms 51 and the driver-guiding tubes 55 downwardly until they are arrested by contact of the arms 51 with adjustable stop screws 75 10 positioned below the arms and mounted as hereinafter described.

Staple drivers 77 (Fig. 6) comprising rods each of a width slightly greater than the length of the head or crossbar of a staple to be driven are located in driver-guiding passages in the tubes 55, and the two staple drivers at each side extend downwardly from the lower ends of a pair of driver bars 79 which are slideable in the tubes 55 and are connected together at their upper ends 15 by a leaf spring 81 (Fig. 1) which serves normally to maintain the lower ends of the two drivers 77 at the same height and yet allows them to settle firmly against the work independently of each other at the end of their staple-driving movements. The upper ends of the two bars 79 at each side are also connected to ball-shaped opposite ends of a short link or rocker 83 on the central portion of which is swiveled a sleeve 85. An upwardly extending operating rod 87 for the two 20 staple drivers is connected at its lower end by a transverse pivot to the sleeve 85 and is connected at its upper end to the forward end of a pivoted forwardly extending spring-operated arm 89. A second rod 91 is also connected at its upper end 25 to the driver-operating arm 89 and is connected at its lower end to an arm 93 which is freely pivoted at 95 (Fig. 3) to the swinging bracket 29. By reason of the pivotal connection between the arm 93 and the bracket 29, the bracket can 30 swing about its pivot 31 without exercising any pulling action on the rod 91. The rod 91 is driven downwardly by the arm 89 in company with the driver bars 79, and at the end of its downward movement a screw 97 carried by the arm 93 is 35 arranged substantially to contact with the upper face of the bracket 29, so that when this bracket is later swung outwardly and upwardly about its pivot 31 after the staple-driving operation through the action of the previously described 40 rack and pinion mechanism, it serves through the rod 91 to raise the driver-operating arm 89 against the resistance of a torsion spring 99 which operates the arm. The arm 89 is held in its up-raised position by a pawl 100 until it is released 45 by the pawl to effect the staple-driving operation in the next cycle of the machine. The pawl is controlled by a cable 102 by which it is connected to cam-operated mechanism (not shown).

A staple carrier or magazine 101 is secured to each driver-guiding tube 55 near the lower end thereof and comprises a metal staple-supporting strip 103 (Figs. 3 and 6) which extends rearwardly and upwardly. The inner end of this strip leads into the driver-guiding passage in the tube 55 substantially at the forward side of the passage (i. e., the side nearer the operator) and near the lower end of the passage so that the staples may pass from the strip directly into the passage. A plurality of unconnected U-shaped staples 104 formed of relatively fine round wire are placed in a row upon each staple-supporting strip 103 by the operator, with the work-penetrating ends of the staples hanging downwardly. A staple-feeding member 105, which is freely 50 movable along an easily removable rod 106 hav-

ing a head 107 secured in place in the magazine by a bayonet joint, straddles the strip 103 and is urged inwardly toward the driver passage by a spring 108 which surrounds the removable rod, the member 105 engaging the outer end of the row of staples to urge them along the supporting strip until the staple at the inner end of the row actually lies within the driver passage in the tube 55. The legs of the staples, as formed in a conventional staple-forming machine, usually 10 diverge somewhat toward their work-penetrating ends, and in order that this fact may not hinder the entry of the staples into the driver guiding passage, the width of which is but little greater than the lengths of the crossbars of the staples, each passage is widened close to the end of the staple-supporting strip 103. Just below the position where the staples enter the passage the sides of the widened portion thereof incline toward each other until the distance between them is but little greater than the length of the staple crossbar. The front and rear walls of the driver-guiding passage are spaced apart a distance substantially equal to the thickness of a single staple. The above-mentioned inwardly 15 inclined sides of the driver-guiding passage serve by engaging the lower ends of the legs of each staple fed into the passage, to maintain the staple in a position opposite the end of the strip 103 until it is forced downwardly by the descent of 20 the staple driver.

A face on each staple magazine 101 extends over the top of the staple-supporting strip 103 and serves to maintain the row of staples correctly seated on the supporting strip. It will 25 be understood that there is no separating member to separate from the row of staples a staple which is to be driven; the row of staples is simply pushed inwardly by pressure of the member 105 on its outer end until the leading staple is 30 arrested by contact with the rear wall of the driver-guiding passage in the path of the driver, the latter being of such limited thickness as on its descent to engage only the crossbar of the leading staple. The staple-supporting strips 103 lead 35 into the driver-guiding passages in such directions that the staples are fed into the passages with their crossbars extending widthwise of the machine or of the shoe. The strips associated 40 with the driver-guiding tubes that are nearest 45 the end of the toe of the shoe are moreover, inclined inwardly toward each other more than the strips associated with the other tubes, as indicated in Fig. 2, so that the crossbars of the staples when driven extend in substantially perpendicular relation to the inwardly curving side edges of the toe portion of the shoe bottom. The crossbars of all the staples, therefore, lie, when 50 they are driven, transversely of the shoe in planes substantially perpendicular to the portions of the 55 side edges of the shoe bottom that are nearest to them, so that the staple legs may reliably straddle the end portions of a binder wire applied around the toe end of the shoe in a manner now 60 to be described.

It will be understood that the previously mentioned wipers 21 are arranged to wipe the marginal portion of the upper materials inwardly against the lip of the insole around the toe and along the sides of the forepart after the last has 65 been forced into the upper. The wipers 21 in the construction herein shown have a groove 111 (Fig. 3) extending horizontally inward at their wiping edges throughout the entire length of these edges, and within this groove a flexible metal binder wire 70 75

or binder indicated at 113 may be positioned by the operator prior to the initial starting of the machine. The wipers of the illustrated machine, like those of the machine shown in the previously mentioned Letters Patent, are of sufficient length to extend along the sides of a shoe in effective engagement with the upper substantially as far as the ball line of the shoe. Arranged forwardly of the ends of the wipers and on about the same level as the wipers are spring-controlled grippers for holding the opposite ends of the binder wire positioned by the operator in the groove in the wipers. Each gripper comprises a pair of gripping fingers or levers 115, 117 (Figs. 4, 5 and 8) extending laterally of the machine and freely pivoted between their opposite end portions on a vertical pin 119, the two pins 119 being secured in lugs projecting forwardly from the forward ends of carrier plates 120 to which the wipers are secured and by movements of which they are operated. Located between the outer ends of each pair of gripping fingers is a compression spring 121 which tends to urge their inner ends together so that the end of the binder wire may be gripped firmly between serrated jaws provided on their inner ends. The outer end of each finger 117 has a tension spring 123 connected to it which pulls rearwardly on the finger and normally maintains its outer end portion in contact with a fixed vertical pin 125 on the machine frame, as shown in Fig. 4. As the wipers are moved forwardly and inwardly to operate on the upper, the outer ends of the fingers 117 are at first held against the fixed pins 125 by the springs 123 and the grippers, therefore, are swung about their pivot pins 119 which advance with the wipers. Accordingly the jaws on the inner ends of the fingers move forward more rapidly than the wipers and thus pull on the ends of the binder wire to draw it forwardly along the groove 111 in the wipers and to pull it tightly around the upstanding marginal portion of the upper forced by the wipers against the lip of the insole. If the wipers continue their movements after the gripping fingers have drawn the wire tightly against the upper, the fingers are moved bodily with them, the outer ends of the fingers 117 being carried away from the pins 125 against the resistance of the springs 123 which are thereby rendered effective to pull the binder still more tightly against the upper, as shown in Fig. 5. This construction and arrangement permits the uppers of shoes of various sizes to be operated upon by the machine without the necessity of changing the wipers, the longitudinal tension applied to the binder wire by the grippers causing the wire to accommodate itself to the shape of the insole lip of each shoe operated upon and therefore to force the margin of the upper hard against the lip all around the portion of the shoe on which the wire acts.

Both the driver-guiding tubes 55 at each side of the shoe are arranged to be swung inwardly over the wipers toward the shoe by inward swinging movement of the bracket 29 associated therewith preparatory to the stapling of the binder wire to the shoe, the tubes being carried downwardly toward the bottom of the shoe during their inward swinging movements by reason of the position of the pivot 31 about which the bracket swings. To permit the lower ends of the tubes to be carried into positions for driving the staples in proper relation to the binder wire so as to fasten the wire firmly to the shoe, there are provided notches 127 in the edges of the wipers to receive the ends of

the tubes, as shown in Figs. 4, 5 and 8, so that the lower ends of the tubes may descend into direct contact with the wire. The lower ends of the tubes have short depending lips 129 (Fig. 3) arranged to abut against the outer side of the wire at the end of the inward swinging movements of the tubes and thus to insure that the staples will straddle the wire correctly, the wire having already been pulled tightly against the upper. The portions of the wipers near their inner edges 10 across which the lower ends of the tubes 55 swing in moving into their staple-inserting positions are beveled inwardly and downwardly toward the notches 127, so that the lower ends of the tubes may descend somewhat below the upper face of 15 the wipers as they approach the shoe upper and the binder wire.

The driver-guiding tubes 55, urged downwardly by the springs 71 which act as described on the arms 51 connected to the tubes, would come into 20 contact with and scrape across the upper face of the wipers soon after the beginning of the swinging movements of the brackets 29 if there were no means to prevent this. In order to avoid such wear on the tubes and the wipers as might result 25 from this scraping action, there is provided means for preventing the lower ends of the tubes from coming into contact with the wipers until they have reached positions close to the edges of the wipers and are over the above-mentioned beveled 30 portions. To this end, the adjustable stop screws 75 against which the two tube-supporting arms 51 at each side of the shoe are urged downwardly by the springs 71 are mounted in inwardly extending lugs 133 formed on an arm 134 (Fig. 1) 35 which is fast on the previously mentioned rotatable pin 33, and there is also fast on this pin at its rear end an upwardly extending lever 135 provided at its upper end with a cam roll 136 in engagement with a stationary outwardly sloping 40 cam member 137 fast on the machine head. As each bracket 29 swings downwardly and inwardly about its pivot 31, the roll 136 is carried downwardly along the cam member 137 which accordingly acts on the lever 135 to swing the lugs 133 45 upwardly and thus to maintain the lower ends of the tubes 55 out of contact with the wipers until they are near the edges of the wipers. When the tubes reach these positions the roll 136 leaves the cam member 137 and thus permits the tubes to 50 be forced by the springs 71 downwardly against the beveled portions of the wipers, so that the lips 129 on the tubes can drop off the inner edges of the wipers into the notches 127 outside of the binder wire, further downward and inward movements of the tubes being then stopped by the wire 55 which is pressed downward and inward against the upper by the pressure of the tubes thereon.

The machine herein shown is further provided with a flexible clamping device 139 (Figs. 2 and 4) 60 which serves, similarly to the toe band shown in the previously mentioned Letters Patent, to wipe the upper upwardly about the toe end of the last in the downward movement of the last and thereafter to clamp the upper against the last near the 65 edge of the insole. As herein illustrated this device comprises a strip of leather 140 supported on a plurality of interconnected curved metal links arranged to extend along the edge of the shoe bottom. Pivotally connected together by a vertical 70 pin 141 located beneath the meeting line of the wipers 21 are two links 143 curved to extend from the center of the extreme toe end of the shoe to points just beyond the corners of the toe, i. e., just beyond the localities where the curvature of 75

the sides of the forepart merges with the curvature across the end of the toe. Connected by vertical pivots to the links 143 are comparatively long links 145 which extend approximately to the ball line of the shoe, and connected by vertical pivots to the links 145 are shorter links 147 which are curved to extend inwardly along the sides of the shoe beyond the ball line and somewhat beyond the portions of the wipers 21 that operate in effective wiping engagement with the upper. The pin 141 that connects the links 143 is fixed against movement lengthwise of the shoe. The forward ends of the links 141 have pivotally connected to them the forward ends of rearwardly extending horizontal toggle links 149 the rear ends of which are pivotally connected to other horizontal toggle links 151 mounted on fixed vertical pivots 153. Rearwardly extending horizontal links 155 are connected at their forward ends to the toggle links 151 by pivot pins 156, and the rear ends of these links 155 are connected to cam-operated mechanism (not shown) by which, before the wipers 21 are operated to wipe the margin of the upper over the insole, straightening movements are imparted to the toggles 149, 151. By such movements of the toggles the links 147 are swung inwardly toward the sides of the shoe and are also moved bodily in directions toward the heel end of the shoe to pull on the other links 143, 145 and cause them to close in tightly around the forepart of the shoe and thus to press the upper against and shape it to the sides of the last. By the construction shown the upper is accordingly shaped closely to the last by the clamping means from the end of the toe to locations somewhat at the rear of the ball line of the shoe where the sides of the shoe slope inwardly toward the waist portion and, as above explained, somewhat rearwardly of the locations where the wipers are effective on the upper.

The grippers 23 already referred to as utilized in place of the upper-clamping members 114 shown in the earlier Letters Patent are shown in Figs. 1 to 5, inclusive, and one of them with its controlling mechanism is also shown in greater detail in Fig. 9. Each gripper comprises an upper jaw 157 and a lower jaw 159 arranged to rest on the upper face of the underlying wiper 21, the upper jaw being movable downwardly to grip the margin of the upper outspread upon the lower jaw. The two jaws are so controlled, as herein-after explained, as to permit them to be pulled inwardly toward the sides of the last by the action of the upper thereon as the last is being forced downwardly into the upper and as the wipers 21 are advancing and closing over the insole. The lower jaw 159 is connected at its outer end by a pivot pin 161 to an upstanding bifurcated lever 163 the lower end of which is mounted on fixed coaxial pivot pins of which one is shown at 165 in Figs. 1 and 9. The upper jaw 157 is pivoted at 167 to the lower jaw and has a curved tail piece 169 which is engaged by a roll 171 carried by a slide 172 movable inwardly and outwardly along the lower jaw, the slide 172 being connected by a link 173 to the upper end of a second upstanding bifurcated lever 175. The lever 175 carries about midway of its length a pin 177 the ends of which extend through slots 179 formed in bushings 180 that are freely rotatable in the lever 163, and by this means the lever 175 is supported on the lever 163 against downward movement. A pair of inwardly extending arms 181 formed on the bushings 180 carry between them a trunnion member 183 through

which extends one end of a rod 185 the other end of which is secured to a member 187 embracing the pin 177. A spring 189 surrounding the rod 185 and bearing at its opposite ends on the members 183 and 187 normally positions the lever 175 in such relation to the lever 163 that the pin 177 is at the outer or right-hand ends (Fig. 9) of the slots 179. The lower bifurcated end of the lever 175 is connected by pivot pins 191 to links 193 (see also Fig. 2) which are pivotally connected to the upper end of one arm of a bell-crank lever 195. The two bell-crank levers 195 at the opposite sides of the structure are coupled together by a link 197. One of these bell-crank levers has a rod 199 connected to it through which operative movements are imparted to both the levers by cam-operated mechanism (not shown), this mechanism being maintained in its normal position by a spring 200.

When the upstanding arms of the bell-crank levers 195 are swung inwardly toward each other at the proper time in the cycle of the machine, the levers 175 are swung about the pins 177 whereby they are fulcrumed on the levers 163, 25 their upper ends moving outwardly and acting through the rolls 171 to swing the upper gripper jaws 157 toward the lower jaws 159 to grip the upper. When the upper jaws have gripped the upper firmly, any continued swinging of the bell-crank levers 195 causes the levers 175 to swing about their connections with the links 173 by reason of the resistance of the gripped upper to their further swinging movements about the pins 177, and as the levers are thus swung about their connections with the links 173 the pins 177 are carried inwardly along the slots 179 against the resistances of the springs 189. Each lever 175 is further provided with an inwardly extending arm 201 to the inner end of which is pivoted a rod 203 which extends downwardly through a hole in a fixed lug 205 (Fig. 2). A spring 207 encircling this rod bears at its lower end against the lug 205 and at its upper end against a nut 209 adjustably threaded on the rod. The spring 207 accordingly tends at all times to swing the lever 175 in an outward direction about its connection with the link 193, and when the pin 177 is at the outer ends of the slots 179, as it is initially, the spring 207 tends also to swing the lever 163 outwardly through the action of the fulcrum pin 177 on this lever. Such outward swinging movements of both levers 175 and 163 are adjustably limited by a stop screw 208 which is threaded in an ear on the lever 163 and bears on a lug 209 (Fig. 2) on the head of the machine. By means of the screws 208 the opposite grippers 23 may accordingly be adjusted toward and from each other. When the levers 175 have been swung to close the two grippers on the upper and the pins 177 have been carried inwardly away from the outer ends of the slots 179, as above described, the springs 207 still tend to impart outward swinging movements to the levers 175; and by reason of the connections established at this time through the closed gripper jaws between the upper ends of the levers 175 and the levers 163 springs 207 still tend also to force the levers 163 outwardly and maintain the screws 208 in contact with the lugs 209. It is accordingly against the resistance of the springs 207 that the grippers may be pulled inwardly toward each other by the upper in the manner previously described as the last is forced down-

wardly into the upper and as the wipers are thereafter closed inwardly over the insole. In the machine herein shown the set of operating instrumentalities further includes at each side thereof a shoe-upper positioning device by use of which insurance may be afforded that the upper is correctly positioned relatively to the means that operates thereon and relatively to the last positioned by the toe plate 13, the presser foot 15 and the toe-end abutment 17. Each device comprises, as shown in Figs. 4, 5, and 10, a horizontal upper-engaging member or plate 211 having a rear edge arranged to extend in a direction substantially perpendicular to the curvature of the edge of the last bottom in the region of the tip line of the upper. The member 211 lies just above the upper face of the underlying wiper 21, and when the parts are in starting positions its rear edge is close to the front side of the gripper 18. The member is secured at its outer end to a forwardly extending threaded stem 213 mounted in bearings in a bracket 215 which is fixed to the forward end of the wiper-carrying plate 120 that is located at the same side of the structure. The stem 213 is keyed to the bracket 215 to maintain the member 211 in a fixed horizontal plane just above the plane of the wipers, and a nut 217 threaded on the forward end of the stem and mounted within a bifurcated portion 219 of the bracket 215 may be rotated to adjust the member 211 forwardly and rearwardly for shoes of different sizes, the forward end of the stem being provided with graduations to facilitate the proper adjustment. On the rear edge of the member 211 there is an upstanding ridge 221 (Fig. 10) arranged to abut against the edge of the toe cap or tip of the shoe upper when the upper is pulled forwardly toward the operator. In order to hold the upper pressed downwardly against the member 211 to insure proper contact between the ridge 221 and the edge of the toe cap, there is provided over each member 211 a member 223. This member is secured at its outer end to a fixed portion 224 (Fig. 10) of the machine frame, and between its outer end and its inner end the member is formed as a flat resilient strip which normally forces the inner end portion of the member down upon the underlying member 211. In order to lift the inner end of the member 223 so as to permit the margin of the upper to be inserted between it and the member 211, there is provided a rotatable cam member 225 in engagement with the lower face of the resilient strip portion of the member 223. The cam member 225 is formed on the rear end of a sleeve 227 (Figs. 4 and 5) which surrounds the stem 213, and clamped on the forward end of this sleeve is a short outwardly extending arm 229. The two arms 229 at the opposite sides of the structure are connected by cables 230 to a single treadle (not shown) by depression of which the sleeves 227 may be turned to lift the members 223 to receive the upper. The two members 211 may be so positioned that when the last is forced into the upper the tip line of the upper will extend across the last at right angles to the median line of the forepart of the last, thus insuring that the opposite ends of the tip line will lie at equal distances from the end of the toe of the finished shoe. Adjustment of the members 211 may be effected by the nuts 217 to determine with great precision the direction in which the tip line extends. It will be understood that by such adjustment the members 211 will not be carried away from beneath the members 223.

As above stated, the members 211 are carried by brackets 215 which are secured to the wiper-carrying plates 120 and accordingly move with the wipers when the latter are operated, while the members 223 are secured to the frame and do not move with the wipers. As the wipers are operated, the members 211 are carried away from beneath the members 223, the upper having already been correctly positioned and having been thereafter firmly gripped by the grippers 18 and 23 and also 10 clamped by the clamping device 139. To permit the members 211 to be returned to their initial positions beneath the members 223 in the return of the wipers to their starting positions, the forward ends of the members 223 are inclined upwardly 15 so that the ridges 221 on the members 211 will pass readily beneath the members 223.

As previously stated, the staples are preferably formed of round wire, and as illustrated the legs of each staple in locations adjacent to the head 20 or crossbar are separated from each other a distance less than the diameter of the binder wire. Since the legs normally diverge from each other, they readily straddle the binder wire when they are driven, and as they are forced into the work 25 the portions of the legs near the crossbar bind against the sides of the wire, as shown in Fig. 7, and wedge it firmly against the work, the crossbar remaining actually out of contact with the wire at the end of the staple-driving operation. 30 If the legs near the crossbar were separated from each other a distance as great as or greater than the diameter of the wire, it would be necessary, in order to secure the wire properly, that the staple be driven far enough into the work for 35 the crossbar to bear firmly against the wire, which would necessitate a very precise adjustment of the length of stroke of the staple driver to insure that the crossbar would be forced with sufficient firmness against the wire without causing it either to shear through the wire or to be crushed against the latter. The use of staples formed as illustrated not only obviates the necessity for such precise adjustment of the stroke of the staple drivers, but also results in the holding 40 of the binder wire more firmly against the upper than would ordinarily be the case if it were pressed against the upper merely by the crossbars of the staples. Since the staples are made of round wire of relatively small diameter, there is but 45 little danger that the needle of the inseam-sewing machine, if it happens to strike a staple, will either break the latter or be broken by it. As illustrated, the work-penetrating ends of the staple legs are blunt, so that the end portions of the 50 legs are more firmly gripped by the wood of the last than they would be if they were sharpened, and are also less likely be deflected out of their 55 normal paths as they are driven into the work.

In the operation of the machine, the operator 60 first takes a flexible binder wire or binder 113 which has been bent approximately to the shape of the toe portion of the lip of a welt shoe insole and tucks it into the groove 111 in the edges of the wipers 21 so that it lies somewhat back of 65 the edges of the wipers, placing the end portions of the wire within the grippers 115, 117 which he opens by pressing on the outer ends of the fingers 115. The operator then depresses the treadle connected to the upper-clamping members 223 to lift these members away from the upper-positioning members 211, and presents a shoe upper, including a toe box and a heel-end counter, upside down with the margin of the forepart of the upper outspread over the wipers 70 75

21 and with the portion of the margin around the extreme toe end extending beneath the clamp members 18. Portions of the margin of the upper located slightly nearer the end of the toe 5 than the tip line are also presented between the open jaws of the grippers 19, and portions thereof located slightly nearer the toe than the ball line are presented between the open jaws of the grippers 23. As the upper is thus presented, portions of the margin located slightly farther from the end of the toe than the tip line lie between the members 211 and 223. The operator next releases the treadle that controls the members 223, whereupon these members by their resiliency 10 press the upper down against the members 211. He then pulls the upper bodily toward him until such movement of the upper is arrested by contact of the ridges 221 on the members 211 with the edge of the toe cap at the opposite side margins of the upper. Having thus positioned the upper correctly in the machine the operator depresses the starting treadle to start the power 15 operation of the machine. As more fully disclosed in the previously mentioned Letters Patent, the arm 7 is thereupon swung part way downward, carrying with it the pivoted block 9 on which are the toe plate 13 and the presser foot 15, the clamp members 18 are moved downwardly to clamp the upper against the wipers and the grippers 19 are closed on the upper. At substantially the same time also the grippers 23 are closed to grip the upper. At the conclusion of 20 these several operations the machine comes automatically to a stop.

25 While the machine is thus at rest the operator takes a last having a welt shoe insole thereon and presents the last to the machine with the toe-end face of the last against the abutment 17 and the insole against the toe plate 13 and the presser foot 15, the toe plate fitting snugly against the inner side of the insole lip around the toe end and the presser foot 15 engaging the insole at the waist portion of the shoe between the portions of the lip located at the opposite sides of the insole. 30 Thereafter, while holding the last in the position thus determined, the operator pulls the heel end of the upper up into the correct position about the heel end of the last, and he then again depresses the starting treadle. The arm 7 is thereupon swung downward and forces the last downward into the forepart of the upper, effecting at the same time an upwiping of the upper about the toe by the clamping device 139. As the last is thus forced downwardly, a pull heightwise of the last is exerted upon the upper by 35 reason of the fact that its margin is clamped on the wipers by the clamp members 18 and is gripped by the grippers 19 and 23, the margin of the upper being partially withdrawn from between the clamp members and the wipers, and the grippers being pulled by the upper somewhat inwardly toward the sides of the last against the resistance of their controlling springs. In the course of the downward movement of the last, 40 moreover, the pads 3 and 5 that underlie the last are depressed against the resistance of their supporting spring, and by reason of the yielding resistance of the pads to the downward movement of the last the block 9 acts through the members 13, 15 and 17, in consequence of relative turning movement between the block and the arm 7, to impart to the last a lengthwise movement forwardly toward the operator and thus to stretch the upper lengthwise, as fully described in the 45 previously mentioned Letters Patent.

When the last arrives in its lowest position, in proper relation to the wipers 21 for the latter to wipe the margin of the upper materials inwardly over the insole, the pads 3 are inflated to press the upper closely against the sides of the last between the toe portion and the heel portion thereof. At substantially the same time the links 155 are operated and act through the toggles 149, 151 to close the forward links 147 of the clamping device 139 inwardly toward the sides of the 50 shoe and to force them also toward the heel end of the shoe, thereby pulling the other links 143 and 145 more tightly about the forepart of the shoe, the links 147 acting to press the upper hard against the last in locations somewhat 55 farther from the toe than the ball line. As the machine continues its operation, the wipers 21 are advanced and closed to wipe the margin of the upper materials over the feather and against the 60 lip of the insole, the wipers at the same time carrying the binder wire 113 inwardly toward the lip. In this operation the wire is drawn tightly against the upstanding margin of the upper around the toe end and along the sides of the forepart by reason of the fact that the 65 portions of the spring-controlled grippers 115, 117 which hold the ends of the wire are advanced lengthwise of the shoe faster than the wipers. In the course of the movement of the wipers the margin of the upper is drawn out 70 from under the clamp members 18, and the grippers 19 and 23 are moved farther inwardly by the pull of the upper upon them. Substantially at the time when the wipers complete their inward wiping movement the clamp members 18 are 75 lifted and the grippers 19 and 23 are opened and returned to their starting positions. While the wipers are then holding the upper pressed closely against the lip of the insole the arm 7 is raised 80 a little to permit the spring which supports the pads 3 and 5 to press the shoe upward more firmly against the lower faces of the wipers.

While the upper is held as above described by the wipers and the binder wire, the swinging brackets 29 which carry the staple-inserting devices are swung downwardly and inwardly about their pivots 31 through the rack and pinion mechanism hereinbefore described. When the lower ends of the driver-guiding tubes 55 approach near the edges of the wipers, after having 85 been held upwardly out of contact with the wipers by the stationary cam members 137, they are released by these members and are forced downwardly by the springs 71 into contact with the wipers. In their further inward movements 90 they may then engage that portion of the margin of the upper that extends upwardly above the wipers and push it inwardly, the depending lips 129 at the lower ends of the tubes then coming into contact with the binder wire lying against the margin of the upper in the notches 127 at the edges of the wipers. By the lips 129 the tubes are accordingly positioned in the proper relation to the wire for the driving of the staples. The tubes, as they engage the wire, are carried inwardly out of contact with the wipers and are pressed 95 downward in the notches 127 by the springs 71 so as to press the binder wire firmly down upon the margin of the upper over the feather of the insole. When the brackets 29 have finished their swinging movements, the pawls 100 are withdrawn from their holding relation to the arms 89, whereupon these arms are operated by the springs 99 to impart to the staple drivers their staple-driving movements. It will be understood that 100

a row of loose staples will have been previously positioned on each of the staple-supporting strips 103 and that the staple-feeding finger 105 for each strip will be pressing against the outer end 5 of the row of staples and accordingly holding the innermost staple in the driver passage. As the several drivers are operated, therefore, the innermost staples are driven with their legs at opposite sides of the binder wire, the wire being 10 wedged between the converging upper end portions of the legs and firmly held thereby against the upper at the end of the staple-driving operation. Two staples are thus driven at each side of the forepart, the positions of the staple-guiding 15 tubes being such that in operating on a shoe of medium size the staple at each side which is nearer the end of the toe is driven in a location at or near the tip line, while the other staple at each side is driven in a location at or near the ball line. The staples, as will be evident, are driven 20 in directions inclined inwardly from the sides of the shoe and also forwardly toward the end of the toe.

After the staples have been driven as above 25 described, the brackets 29 are swung outwardly to their starting positions by reverse movement of their operating mechanism. In such return movements of the brackets the cam rolls 136 are engaged by outwardly and upwardly sloping lower 30 faces of the cam members 137, so that these members act to lift the arms 51 and the tubes 55. Since, however, the cam members are not immediately effective to lift the tubes out of the notches 127 in the wipers so as to clear the edges 35 of the wipers, and since the tubes cannot swing outwardly with the brackets 29 until their lower ends are clear of the edges of the wipers, the springs 61 yield during the initial portion of the outward swinging movements of the brackets and 40 the tubes remain substantially stationary. As soon as the lower ends of the tubes are lifted above the wipers the springs 61 pull them outwardly into contact with the stop screws 63. The outward swinging movements of the brackets 29 serve through the rods 91 to lift the driver-operating arms 89 against the resistances of the 45 springs 99 and to retract the staple drivers to their normal positions, the arms 89 being thereafter retained in their upraised positions by the 50 pawls 100.

After the staple-inserting devices have been returned to their starting positions the wipers 21 remain for a predetermined time in holding relation to the margin of the upper during a dwell 55 in the cycle of operations of the machine, and then the machine is automatically started into operation again in the manner disclosed in the previously mentioned Letters Patent. As the wipers are retracted they leave the binder wire 60 in upper-holding position. After the machine has finally come to a stop the operator releases the ends of the binder wire from the grippers 115, 117 by opening these grippers, and then removes the shoe from the machine. Thereafter 65 the shoe may, for example, be subjected successively to the operations of a heel-seat lasting machine and a combined welt-sewing and side-lasting machine, as further suggested in the above-mentioned Letters Patent.

Although, as above stated, the inward movements of the staple-guiding tubes 55 normally terminate with their lower ends in contact with the binder wire in the notches 127 at the edges 70 of the wipers, it may happen that when the same 75 wipers are used for lasting shoes of different sizes

or styles the portions of the wipers where the notches that are farthest from the end of the toe are located will under some conditions not press the upper closely inward against the lip 10 of the insole. Under these conditions the staple-guiding tubes that are located farthest from the end of the toe may, upon contact with the binder wire, carry it inwardly beyond the edges of the wipers and force it firmly inward and downward 15 against the marginal portion of the upper, at the same time acting through the binder wire to force these portions of the upper firmly against the feather and the lip of the insole. Substantial insurance is accordingly afforded 20 that even under these conditions the binder wire will be properly positioned and fastened to the shoe. Furthermore, as the grippers which grip the ends of the wire are carried outwardly away from the shoe by the opening movements of the wipers, they serve to bend the end portions of 25 the wire more or less about the staples located substantially at the ball of the shoe and thus further insure that in case the staples have not been driven far enough into the shoe to grip the wire securely, the wire will nevertheless be held 30 tightly against the upper around the forepart by the staples.

Having described the invention, what I claim 35 as new and desire to secure by Letters Patent of the United States is:

1. In a machine for shaping uppers over lasts, the combination with end-embracing wipers movable lengthwise and widthwise of a last to wipe the marginal portion of an upper around an end of the last into lasted position, of mechanism constructed and arranged to engage a binder 35 extending around the end of the upper and movable relatively to said wipers to force the binder against the marginal portion of the upper in the course of the operative movement of 40 the wipers.

2. In a machine for shaping uppers over lasts, the combination with end-embracing wipers movable lengthwise and widthwise of a last to wipe the marginal portion of an upper around 45 an end of the last into lasted position, of mechanism constructed and arranged to engage a binder extending around the end of the upper and movable relatively to said wipers to pull the binder lengthwise of the last against the marginal 50 portion of the upper in the course of the operative movement of the wipers.

3. In a machine for shaping uppers over lasts, the combination with toe-embracing wipers movable lengthwise and widthwise of a last to wipe 55 the marginal portion of an upper around the toe end of the last into lasted position, of devices constructed and arranged to engage at the opposite sides of the last portions of a flexible binder extending around the toe end of the upper, said devices being movable relatively to the wipers to pull the binder lengthwise of the last 60 into holding relation to the marginal portion of the upper in the course of the operative movement of the wipers.

4. In a machine for shaping uppers over lasts, the combination with end-embracing wipers movable to wipe the marginal portion of an upper around an end of a last into lasted position, of mechanism constructed and arranged to engage 70 a binder extending around the end of the upper, said mechanism being movable relatively to the wipers to pull the binder into holding relation to the marginal portion of the upper in response to the operative movement of the wipers.

5. In a machine for shaping uppers over lasts, the combination with toe-embracing wipers movable to wipe the marginal portion of an upper around the toe end of a last into lasted position, of devices constructed and arranged to engage at the opposite sides of the last portions of a flexible binder extending around the toe end of the upper, the binder-engaging portions of said devices being movable lengthwise of the last relatively to the wipers in response to the operative movement of the wipers to pull the binder against the marginal portion of the upper.
6. In a machine for shaping uppers over lasts, the combination with toe-embracing wipers movable to wipe the marginal portion of an upper around the toe end of a last into lasted position, of grippers constructed and arranged to grip at the opposite sides of the last portions of a flexible binder extending around the toe end of the upper, and means for moving said grippers lengthwise of the last relatively to the wipers in the course of the operative movement of the wipers to pull the binder into holding relation to the marginal portion of the upper.
7. In a machine for shaping uppers over lasts, the combination with toe-embracing wipers movable to wipe the marginal portion of an upper around the toe end of a last into lasted position, of grippers constructed and arranged to grip at the opposite sides of the last portions of a flexible binder extending around the toe end of the upper, said grippers being mounted for swinging movements about axes extending heightwise of the last, and means for swinging said grippers to pull the binder into holding relation to the marginal portion of the upper in the course of the operative movement of the wipers.
8. In a machine for shaping uppers over lasts, the combination with end-embracing wipers movable to wipe the marginal portion of an upper around an end of a last into lasted position, of gripping means mounted to move with the wipers and constructed and arranged to grip a flexible binder extending around the end of the upper, and mechanism for also moving said gripping means relatively to the wipers in response to the movement of the wipers to pull the binder into holding relation to the marginal portion of the upper.
9. In a machine for shaping uppers over lasts, the combination with toe-embracing wipers movable to wipe the marginal portion of an upper around the toe end of a last into lasted position, of devices constructed and arranged to engage at the opposite sides of the last portions of a flexible binder extending around the toe end of the upper, supports for said devices mounted to move with the wipers, and means for moving said devices relatively to the wipers to pull the binder into holding relation to the marginal portion of the upper in the course of the operative movement of the wipers.
10. In a machine for shaping uppers over lasts, the combination with toe-embracing wipers movable to wipe the marginal portion of an upper around the toe end of a last into lasted position, of devices constructed and arranged to engage at the opposite sides of the last portions of a flexible binder extending around the toe end of the upper, supports for said devices mounted to move with the wipers and on which the devices are mounted for swinging movements, and means for swinging said devices relatively to their supports to pull the binder into holding relation to the marginal portion of the upper in response to the operative movement of the wipers.
11. In a machine for shaping uppers over lasts, the combination with toe-embracing wipers movable to wipe the marginal portion of an upper around the toe end of a last into lasted position, of grippers constructed and arranged to grip at the opposite sides of the last portions of a flexible binder extending around the toe end of the upper, supports for said grippers mounted to move with the wipers and on which the grippers are mounted for swinging movements, and means arranged to act on said grippers in the course of the operative movement of the wipers to cause them to swing relatively to their supports in directions to pull the binder into holding relation to the marginal portion of the upper.
12. In a machine for shaping uppers over lasts, the combination with toe-embracing wipers movable to wipe the marginal portion of an upper around the toe end of a last into lasted position, of grippers constructed and arranged to grip at the opposite sides of the last portions of a flexible binder extending around the toe end of the upper, said grippers comprising levers arranged to extend widthwise of the last and to grip the binder at their inner ends, supports for said levers mounted to move with the wipers and on which the levers are mounted to swing about axes located between their opposite ends and extending heightwise of the last, and springs connected to the outer ends of said levers for swinging them to pull the binder against the marginal portion of the upper in response to the movement of the wipers.
13. In a machine for shaping uppers over lasts, the combination with toe-embracing wipers movable to wipe the marginal portion of an upper around the toe end of a last into lasted position, of grippers constructed and arranged to grip at the opposite sides of the last portions of a flexible binder extending around the toe end of the upper, said grippers comprising levers arranged to extend widthwise of the last and to grip the binder at their inner ends, supports for said levers mounted to move with the wipers and on which the levers are mounted to swing about axes located between their opposite ends and extending heightwise of the last, springs connected to the outer ends of said levers for swinging them to pull the binder against the marginal portion of the upper in response to the movement of the wipers.
14. In a machine for shaping uppers over lasts, end-embracing wipers movable to wipe the marginal portion of an upper around an end of a last into lasted position, said wipers having at their wiping edges a groove arranged to receive an upper-holding binder, and means movable relatively to the wipers to force said binder into holding relation to the marginal portion of the upper in the course of the operative movement of the wipers.
15. In a machine for shaping uppers over lasts, end-embracing wipers movable to wipe the marginal portion of an upper around an end of a last into lasted position, said wipers having at their wiping edges a groove arranged to receive an upper-holding binder, and gripper jaws arranged to grip the binder between them and

movable relatively to the wipers to pull the binder into holding relation to the marginal portion of the upper.

16. In a machine for shaping uppers over lasts, 5 toe-embracing wipers movable to wipe the marginal portion of an upper around the toe end of a last into lasted position, said wipers having at their wiping edges a groove arranged to receive an upper-holding binder, gripper jaws arranged 10 to grip the binder between them at the opposite sides of the last beyond the ends of the wipers, and means for moving said gripper jaws lengthwise of the last relatively to the wipers to pull the binder into holding relation to the marginal 15 portion of the upper.

17. In a machine for shaping uppers over lasts, toe-embracing wipers movable to wipe the marginal portion of an upper around the toe end of a last into lasted position, said wipers having 20 at their wiping edges a groove arranged to receive an upper-holding binder placed therein prior to their operation on a shoe, and means for moving said binder relatively to the wipers to pull it into holding relation to the marginal portion of the 25 upper in the course of the operative movement of the wipers.

18. In a machine for shaping uppers over lasts, toe-embracing wipers movable to wipe the marginal portion of an upper around the toe end of a last into lasted position, said wipers having at 30 their wiping edges a groove arranged to receive an upper-holding binder placed therein prior to their operation on a shoe, and mechanism automatically movable relatively to the wipers in response to their operative movement to pull the binder into holding relation to the marginal portion of the upper.

19. In a machine for shaping uppers over lasts, toe-embracing wipers movable to wipe the marginal portion of an upper around the toe end of a last into lasted position, said wipers having at 40 their wiping edges a groove arranged to receive an upper-holding binder placed therein prior to their operation on a shoe, grippers arranged to 45 grip the binder at the opposite sides of the last, supports for said grippers mounted to move with the wipers and on which the grippers are mounted for swinging movements, and means arranged to act on said grippers to cause them to swing in 50 directions to pull the binder against the marginal portion of the upper in response to the operative movement of the wipers.

20. In a machine for shaping uppers over lasts, the combination with end-embracing wipers movable to wipe the marginal portion of an upper around an end of a last into lasted position, of 55 mechanism constructed and arranged to engage a binder extending around the end of the upper and movable relatively to the wipers to force the binder into holding relation to the marginal portion of the upper in the course of the operative movement of the wipers, and means for fastening the binder to the shoe in upper-holding position.

21. In a machine for shaping uppers over lasts, 60 the combination with toe-embracing wipers movable to wipe the marginal portion of an upper around the toe end of a last into lasted position, of devices constructed and arranged to engage at the opposite sides of the last portions of a 65 binder extending around the toe end of the upper and movable relatively to the wipers to pull the binder into holding relation to the marginal portion of the upper in the course of the operative movement of the wipers, and means for driving 70 fastenings at the opposite sides of the shoe bot-

tom to fasten the binder in upper-holding position.

22. In a machine for shaping uppers over lasts, 5 the combination with toe-embracing wipers movable to wipe the marginal portion of an upper around the toe end of a last into lasted position, of mechanism constructed and arranged to engage a binder extending around the toe end of the upper and movable relatively to the wipers to force the binder into holding relation to the 10 marginal portion of the upper, and means for driving fastenings in locations nearer the end of the toe than the rear ends of the wiping edges of the wipers to fasten the binder in upper-holding position. 15

23. In a machine for shaping uppers over lasts, the combination with toe-embracing wipers movable to wipe the marginal portion of an upper around the toe end of a last into lasted position, 20 of grippers comprising jaws constructed and arranged to grip between them at the opposite sides of the last portions of a binder extending around the toe end of the upper and movable relatively to the wipers to pull the binder into holding relation to the marginal portion of the upper in response to the operative movement of the wipers, 25 and means for driving fastenings at the opposite sides of the shoe bottom to fasten the binder in upper-holding position.

24. In a machine for shaping uppers over lasts, 30 the combination with toe-embracing wipers movable to wipe the marginal portion of an upper around the toe end of a last into lasted position, 35 of grippers comprising jaws constructed and arranged to grip between them at the opposite sides of the last portions of a binder extending around the toe end of the upper and movable relatively to the wipers to pull the binder into holding relation to the marginal portion of the upper, and means for driving fastenings in locations nearer the end of the toe than the rear ends of the wiping edges of the wipers to fasten 40 the binder in upper-holding position.

25. In a machine for shaping uppers over lasts, toe-embracing wipers movable to wipe the marginal portion of an upper around the toe end of a last into lasted position, said wipers having at 45 their wiping edges a groove arranged to receive an upper-holding binder, devices located beyond the ends of the wipers and movable relatively to the wipers in directions lengthwise of the shoe to pull the binder into holding relation to the marginal portion of the upper, and means for driving fastenings at the opposite sides of the shoe bottom to fasten the binder in upper-holding 50 position. 55

26. In a machine for shaping uppers over lasts, toe-embracing wipers movable to wipe the marginal portion of an upper around the toe end of a last into lasted position, said wipers having at 60 their wiping edges a groove arranged to receive an upper-holding binder and having also at said edges notches in which to drive fastenings to fasten the binder in upper-holding position, means located beyond the ends of the wipers and movable relatively to the wipers to pull the binder into holding relation to the marginal portion of the upper, and means for driving fastenings in 65 said notches in the wipers to fasten the binder.

27. In a machine for shaping uppers over lasts, 70 means for working an upper into lasted position around the toe end of a last and along the sides thereof substantially as far rearwardly as the ball line of the shoe, and means for fastening to the shoe an upper-holding binder applied about 75

- the forepart, said fastening means comprising devices for driving fastenings into holding relation to the binder in locations at the ball portion of the shoe.
- 5 28. In a machine for shaping uppers over lasts, means for working an upper into lasted position around the toe end of a last and along the sides thereof substantially as far rearwardly as the ball line of the shoe, and means for fastening to the shoe an upper-holding binder applied about the forepart, said fastening means comprising devices for driving fastenings into holding relation to the binder in locations near the ends of the tip line of the upper and also in locations at the ball portion of the shoe. 10
- 15 29. In a machine for shaping uppers over lasts, means for working an upper into lasted position around the toe end of a last and along the sides thereof substantially as far rearwardly as the ball line of the shoe and for also applying a flexible binder around the marginal portion of the upper in those locations, and means for driving fastenings into the shoe to fasten the binder in locations near the ends of the tip line of the upper and also in locations at the ball portion of the shoe. 20
- 25 30. In a machine for shaping uppers over lasts, wipers movable to wipe the marginal portion of an upper into lasted position around the toe end of a last and along the sides of the last substantially as far rearwardly as the ball line of the shoe, means for pulling a binder into holding relation to the marginal portion of the upper in those locations, and means for driving fastenings 30 to fasten the binder to the shoe in locations near the ends of the tip line of the upper and also in locations at the ball portion of the shoe. 35
- 35 31. In a machine for shaping uppers over lasts, wipers movable to wipe the marginal portion of an upper into lasted position around the toe end of a last and along the sides of the last substantially as far rearwardly as the ball line of the shoe, said wipers having at their wiping edges a groove arranged to receive an upper-holding binder and having also at said edges notches in which to drive fastenings in locations near the ends of the tip line of the upper end in locations at the ball portion of the shoe to fasten the binder, and means for driving said fastenings into holding relation to the binder. 40
- 45 32. In a machine for shaping uppers over lasts, means for working an upper into lasted position around the toe end of a last and along the sides thereof substantially as far rearwardly as the ball line of the shoe, said means comprising wipers having at their wiping edges a groove arranged to receive an upper-holding binder, and means for fastening the binder to the shoe comprising devices for driving fastenings into holding relation to the binder in locations at the ball portion of the shoe. 50
- 55 33. In a machine for shaping uppers over lasts, means for working an upper into lasted position around the toe end of a last and for also applying a binder in holding relation to the marginal portion of the upper around the toe, and devices constructed and arranged to drive fastenings at the opposite sides of the shoe bottom into holding relation to the binder in directions inclined inwardly away from the edge of the shoe bottom and also forwardly toward the end of the toe to fasten the binder in upper-holding position. 60
- 65 34. In a machine for shaping uppers over lasts, means for working an upper into lasted position around the toe end of a last and for also applying a binder in holding relation to the marginal portion of the upper around the toe, and devices constructed and arranged to drive fastenings at the opposite sides of the shoe bottom staples straddling the binder to fasten the binder in upper-holding position, said devices comprising guides for the staples so arranged as to direct the staples inwardly from the edge of the shoe bottom and also forwardly toward the end of the toe. 5
- 70 35. In a machine for shaping uppers over lasts, means for working an upper into lasted position around the toe end of a last and for also applying a binder in holding relation to the marginal portion of the upper around the toe, said means comprising toe-embracing wipers for wiping the marginal portion of the upper around the toe into lasted position, and means for driving at the opposite sides of the shoe bottom staples straddling the binder in locations between the front and rear ends of the wiping edges of the wipers to fasten the binder in upper-holding position. 10
- 75 36. In a machine for shaping uppers over lasts, means for working an upper into lasted position around the toe end of a last and for also applying a binder to the marginal portion of the upper around the toe to hold the upper in lasted position, and means for driving over the binder at the opposite sides of the shoe bottom staples the legs of which diverge from each other toward their work-penetrating ends and are spaced from each other near their crossbars by distances less than the diameter of the binder to cause them to clamp the binder between them as they are driven. 25
- 80 37. That improvement in methods of fastening a binder wire in upper-holding position around an end of a shoe bottom which consists in providing staples the legs of which diverge from each other toward their work-penetrating ends and are spaced from each other near their crossbars by distances less than the diameter of the wire, and driving said staples over the wire far enough into the work to cause the staple legs to clamp the wire between them near their crossbars. 40
- 85 38. That improvement in methods of fastening a binder wire in upper-holding position around an end of a shoe bottom which consists in providing staples the legs of which diverge from each other toward their work-penetrating ends and are spaced from each other near their crossbars by distances less than the diameter of the wire, and driving said staples over the wire far enough into the work to cause the legs of the staples near their crossbars to clamp the wire between them while leaving the crossbars spaced from the wire. 45
- 90 39. That improvement in methods of fastening a binder wire in upper-holding position around an end of a shoe bottom which consists in providing staples having diverging legs that are blunt at their work-penetrating ends and are spaced from each other near the crossbars by distances less than the diameter of the wire, and driving said staples over the wire into the shoe and last far enough to cause their legs near the crossbars to clamp the wire between them. 50
- 95 40. In a machine for shaping uppers over lasts, means for working an upper into lasted position around the toe end of a last and for also applying to the marginal portion of the upper around the toe a binder for holding the upper in lasted position, said means comprising toe-embracing 65
- 100 75

- wipers provided with notches at their wiping edges, and devices for inserting fastenings to fasten the binder in upper-holding position, said devices comprising guides for the fastenings movable into said notches in the wipers prior to the insertion of the fastenings.
41. In a machine for shaping uppers over lasts, means for working an upper into lasted position around the toe end of a last and for also applying to the marginal portion of the upper around the toe a binder for holding the upper in lasted position, said means comprising toe-embracing wipers provided with notches at their wiping edges, and devices for inserting fastenings to fasten the binder in upper-holding position, said devices comprising guides for the fastenings movable relatively to the wipers both heightwise and widthwise of the shoe into positions in said notches in the wipers prior to the insertion of the fastenings.
42. In a machine for shaping uppers over lasts, means for working an upper into lasted position around the toe end of a last and for also applying to the marginal portion of the upper around the toe a binder for holding the upper in lasted position, said means comprising toe-embracing wipers provided with notches at their wiping edges, and devices constructed and arranged to drive staples over the binder in said notches to fasten the binder in upper-holding position, said devices comprising guides for the staples movable to positions in said notches prior to the driving of the staples.
43. In a machine for shaping uppers over lasts, means for working an upper into lasted position around the toe end of a last and for also applying a binder to the marginal portion of the upper around the toe to hold the upper in lasted position, and devices for inserting fastenings to fasten the binder in upper-holding position, said devices being movable relatively to said means into engagement with the binder to press it upon the upper prior to the insertion of the fastenings.
44. In a machine for shaping uppers over lasts, means for working an upper into lasted position around the toe end of a last and for also applying a binder to the marginal portion of the upper around the toe to hold the upper in lasted position, said means comprising toe-embracing wipers having notches at their wiping edges, and devices for inserting fastenings in said notches to fasten the binder in upper-holding position, said devices comprising guides for the fastenings movable into said notches and against the binder to press the binder upon the upper prior to the insertion of the fastenings.
45. In a machine for shaping uppers over lasts, means for working an upper into lasted position around the toe end of a last and for also applying a binder to the marginal portion of the upper around the toe to hold the upper in lasted position, and devices for inserting fastenings to fasten the binder in upper-holding position, said devices being movable into positions to press the binder against the upper both heightwise and laterally of the shoe prior to the insertion of the fastenings.
46. In a machine for shaping uppers over lasts, means for working an upper into lasted position around the toe end of a last and for also applying a binder to the marginal portion of the upper around the toe to hold the upper in lasted position, and devices for inserting fastenings to fasten the binder in upper-holding position, said devices being movable laterally of the shoe into fastening-inserting positions and having thereon projections arranged to engage the binder and to press it inwardly against the marginal portion of the upper.
47. In a machine for shaping uppers over lasts, means for working an upper into lasted position around the toe end of a last and for also applying a binder to the marginal portion of the upper around the toe to hold the upper in lasted position, and devices for inserting fastenings to fasten the binder in upper-holding position, said devices comprising guides for the fastenings movable both heightwise and laterally of the shoe into fastening-inserting positions and provided with means for engaging the binder and pressing it upon the upper both heightwise and laterally of the shoe prior to the insertion of the fastenings.
48. In a machine for shaping uppers over lasts, wipers for wiping an upper into lasted position around an end of a last with its marginal portion upstanding on the shoe bottom, and devices for inserting fastenings at the opposite sides of the shoe bottom to fasten a binder against said upstanding marginal portion of the upper, said devices being movable laterally of the shoe relatively to the wipers into fastening-inserting positions and being constructed and arranged to engage a binder and press it inwardly against the upstanding marginal portion of the upper.
49. In a machine for shaping uppers over lasts, wipers for wiping an upper into lasted position around an end of a last with its marginal portion upstanding on the shoe bottom, and devices for inserting fastenings at the opposite sides of the shoe bottom to fasten a binder against said upstanding marginal portion of the upper, said devices being movable laterally of the shoe relatively to the wipers into fastening-inserting positions and comprising guides for the fastenings having projections thereon arranged to engage the binder on its outer side and to press it inwardly against the upstanding marginal portion of the upper.
50. In a machine for shaping uppers over lasts, means for working an upper into lasted position around an end of a last with its marginal portion upstanding on the shoe bottom, and devices for inserting fastenings at the opposite sides of the shoe bottom to fasten a binder against said upstanding marginal portion of the upper, said devices comprising guides for the fastenings movable both heightwise and laterally of the shoe into fastening-inserting positions and constructed and arranged to engage the binder and to press it both toward the bottom face of the last and inwardly against the upstanding marginal portion of the upper prior to the insertion of the fastenings.
51. In a machine for shaping uppers over lasts, wipers for wiping an upper into lasted position around an end of a last with its marginal portion upstanding on the shoe bottom, and devices for inserting staples at the opposite sides of the shoe bottom to fasten a wire binder against the upstanding marginal portion of the upper, said devices comprising guides for the staples movable laterally of the shoe relatively to the wipers into staple-inserting positions and having thereon projections arranged to engage the binder on its outer side to position said guides in proper relation to the binder for the driving of the staples.
52. In a machine for shaping uppers over lasts, means for working an upper into lasted position

with its marginal portion upstanding on the shoe bottom, and means for fastening an upper-holding binder against the upstanding marginal portion of the upper comprising a guide for fastenings movable both heightwise of the shoe and inwardly over the shoe bottom to engage and press the binder against the upper prior to the driving of a fastening from said guide.

53. In a machine for shaping uppers over lasts, means for working an upper into lasted position with its marginal portion upstanding on the shoe bottom, and means for fastening an upper-holding binder against the upstanding marginal portion of the upper comprising a guide for staples movable inwardly over the shoe bottom into staple-inserting position and having thereon a projection movable into engagement with the binder on the outer side of the latter to press the binder inwardly and to position the guide in proper relation to the binder for the driving of a staple.

54. In a machine for shaping uppers over lasts, wipers for embracing an upper around an end of a last and wiping the marginal portion of the upper into lasted position, and means for fastening to the shoe an upper-holding binder applied over the shoe bottom around the marginal portion of the upper, said fastening means comprising a guide for fastenings movable relatively to the wipers into engagement with the binder to press the binder against the upper prior to the driving of a fastening.

55. In a machine for shaping uppers over lasts, means for working an upper into lasted position around an end of a last, and devices for inserting fastenings at the opposite sides of the shoe bottom to fasten to the shoe a binder applied around the end of the upper, said devices comprising guides for the fastenings normally spaced from said means and movable laterally of the shoe into fastening-inserting positions and also magazines for fastenings movable with said guides.

56. In a machine for shaping uppers over lasts, means for working an upper into lasted position around the toe end of a last and for also applying a binder to the marginal portion of the upper around the toe to hold the upper in lasted position, and devices for inserting staples at the opposite sides of the shoe bottom in clamping relation to the binder to fasten the binder in upper-holding position, said devices comprising guides for the staples movable relatively to said means laterally of the shoe into staple-inserting positions and also magazines for staples movable with said guides.

57. In a machine for shaping uppers over lasts, end-embracing wipers for wiping an upper into lasted position around an end of a last, said wipers having notches at their wiping edges, and devices for inserting upper-holding fastenings in said notches in the wipers, said devices comprising guides for the fastenings movable into positions in said notches prior to the insertion of the fastenings.

58. In a machine for shaping uppers over lasts, the combination with end-embracing wipers for wiping the marginal portion of an upper around an end of a last into lasted position, of fastening-inserting devices comprising guides for fastenings movable both heightwise and laterally of the shoe into positions for driving fastenings substantially at the edges of said wipers, means for moving said guides inwardly along the wipers, spring means tending to move said guides heightwise of the shoe toward the wipers during their

inward movements, and means for holding the guides retracted out of contact with the wipers against the resistance of said spring means during a portion of their inward movements and for then releasing them to the action of said spring means. 5

59. In a machine for shaping uppers over lasts, the combination with end-embracing wipers for wiping the marginal portion of an upper around an end of a last into lasted position, of fastening-inserting devices comprising guides for fastenings movable both heightwise and laterally of the shoe into positions for driving fastenings substantially at the edges of said wipers, brackets mounted for swinging movements to carry said guides inwardly along the wipers, arms mounted for swinging movements on said brackets to control movements of said guides heightwise of the shoe, springs arranged to act on said arms and tending to force the guides toward the wipers, 15 and cam means arranged to act on said arms to hold the guides retracted from the wipers during a portion of their inward movements and then to release them. 20

60. In a machine for shaping uppers over lasts, end-embracing wipers for wiping the marginal portion of an upper around an end of a last into lasted position, said wipers having notches at their wiping edges, fastening-inserting devices comprising guides for fastenings movable both heightwise and laterally of the shoe into positions in said notches for driving the fastenings, means for moving said guides inwardly along the wipers, spring means tending to move said guides heightwise of the shoe toward the wipers during 35 their inward movements, and means for holding the guides retracted out of contact with the wipers against the resistance of said spring means in their inward movements until they arrive approximately in positions to enter said notches 40 and for then releasing them to the action of said spring means.

61. In a machine for shaping uppers over lasts, the combination with upper-shaping means, of means comprising a pair of driver bars for driving fastenings in different locations to fasten the upper, spring means connecting said driver bars together to maintain them in a normal initial relation to each other and yieldable to permit relative lengthwise movement of the bars in 50 the driving of the fastenings, and means for operating said bars to drive the fastenings.

62. In a machine for shaping uppers over lasts, the combination with upper-shaping means, of means comprising a pair of driver bars for driving fastenings in different locations to fasten the upper, a leaf spring connecting said driver bars together to maintain them in a normal initial relation to each other and yieldable to permit relative lengthwise movement of the bars in the 55 driving of the fastenings, and means for operating said bars to drive the fastenings.

63. In a machine for shaping uppers over lasts, the combination with upper-shaping means, of means comprising a pair of driver bars for driving fastenings in different locations to fasten the upper, a member for operating said driver bars, connections between said member and the driver bars so constructed as to permit relative lengthwise movement of the bars in the driving of 70 the fastenings, and spring means connecting said bars together to maintain them in a normal initial relation to each other and yieldable to permit said relative movement of the bars.

64. In a machine for shaping uppers over lasts, 75

- the combination with upper-shaping means, of means comprising a pair of driver bars for driving fastenings in different locations to fasten the upper, a rocker connected at its opposite ends to said driver bars for operating them while permitting relative lengthwise movement of the bars in the driving of the fastenings, an operating member connected to said rocker between its opposite ends, and a leaf spring fastened to 5 said driver bars for maintaining them in a normal initial relation to each other and yieldable to permit said relative movement of the bars.
65. In a machine for shaping uppers over lasts, the combination with means for working an upper into lasted position around the toe end of 10 a last, of means for driving at each side of the shoe bottom a pair of fastenings spaced apart lengthwise of the edge of the shoe bottom to fasten an upper-holding binder against the upper, said driving means comprising a pair of driver bars for driving each pair of fastenings, means for operating said driver bars so constructed as to permit relative lengthwise movement of the two bars at each side of the shoe 15 bottom in the driving of the fastenings, and spring means connecting the two bars at each side together to maintain them in a normal initial relation to each other and yieldable to permit said relative movement of the bars.
- 30 66. In a machine for shaping uppers over lasts, the combination with means for working an upper into lasted position around the toe end of a last, of means for driving at each side of the shoe bottom a pair of fastenings spaced apart 20 lengthwise of the edge of the shoe bottom to fasten an upper-holding binder against the upper, said driving means comprising a pair of driver bars for driving each pair of fastenings, means for operating said driver bars comprising for 25 each pair of bars a rocker connected to the bars to permit them to move lengthwise relatively to each other in the driving of the fastenings, and a leaf spring connecting the two bars at each side together to maintain them in a normal initial relation to each other and yieldable to 30 permit their relative movement.
67. In a machine for shaping uppers over lasts, the combination with means for wiping an upper heightwise of a last around the forepart 35 of the last, of grippers comprising jaws constructed and arranged to grip the marginal portion of the upper outspread between them in locations at the opposite sides of the toe portion, and other grippers comprising jaws for similarly gripping the marginal portion of the upper 40 between them in locations farther rearwardly along the sides of the last than said toe portion, all said grippers being movable inwardly toward the sides of the last in response to the 45 pull of the upper thereon in the wiping operation.
68. In a machine for shaping uppers over lasts, upper-shaping means comprising wipers constructed and arranged to extend around the toe 50 end of a last and substantially as far rearwardly as the ball line of the shoe for wiping the marginal portion of the upper inwardly, grippers comprising jaws constructed and arranged to grip between them the marginal portion of the upper 55 outspread over the wipers in locations at the opposite sides of the toe portion, and other grippers comprising jaws for similarly gripping the marginal portion of the upper between them in locations substantially at the ball portion of 60 the shoe, all said grippers being movable inwardly 65

toward the last in response to the pull of the upper thereon in the upper-shaping operation.

69. In a machine for shaping uppers over lasts, upper-shaping means including wipers constructed and arranged to extend around the toe end of a last and substantially as far rearwardly as the ball line of the shoe for wiping the marginal portion of the upper inwardly, means for moving the last heightwise relatively to said upper-shaping means to shape the upper over the top 10 and sides of the forepart of the last, grippers comprising jaws constructed and arranged to grip between them the marginal portion of the upper outspread over the wipers in locations approximately at the ends of the tip line of the 15 upper, and other grippers comprising jaws for similarly gripping the marginal portion of the upper between them in locations substantially at the ball portion of the shoe, all said grippers being movable inwardly toward the sides of the 20 last in response to the pull of the upper thereon in the upper-shaping operation.

70. In a machine for shaping uppers over lasts, the combination with upper-shaping means comprising wipers movable to wipe the marginal 25 portion of an upper inwardly at the opposite sides of the forepart of a last, of grippers constructed and arranged to grip the marginal portion of the upper outspread over the wipers at the opposite sides of the forepart and movable 30 inwardly toward the last in response to the pull of the upper thereon in the upper-shaping operation, each of said grippers comprising a pair of upper-gripping jaws, a lever mounted for swinging movement widthwise of the last and 35 connected to one of the pair of jaws, a second lever mounted for swinging movement widthwise of the last for operating the other jaw to grip the upper, and spring means against the resistance of which both said levers are movable 40 with the gripper inwardly toward the last in response to the pull of the upper on the gripper.

71. In a machine for shaping uppers over lasts, the combination with upper-shaping means comprising wipers movable to wipe the marginal portion 45 of an upper inwardly at the opposite sides of the forepart of a last, of grippers constructed and arranged to grip the marginal portion of the upper outspread over the wipers at the opposite sides of the forepart and movable inwardly toward the last in response to the pull of the upper thereon in the upper-shaping operation, each of 50 said grippers comprising a pair of upper-gripping jaws, a lever mounted for swinging movement widthwise of the last and connected to one of the pair of jaws, a second lever mounted for swinging movement widthwise of the last for operating the other jaw to grip the upper, and a spring arranged to act on said second lever to maintain the grip on the upper and to oppose 55 yieldingly movements of both levers inwardly toward the last with the gripper in response to the pull of the upper on the gripper.

72. In a machine for shaping uppers over lasts, the combination with upper-shaping means comprising wipers movable to wipe the marginal portion 60 of an upper inwardly at the opposite sides of the forepart of a last, of grippers constructed and arranged to grip the marginal portion of the upper outspread over the wipers at the opposite sides of the forepart and movable inwardly toward the last in response to the pull of the upper thereon in the upper-shaping operation, each of said grippers comprising a pair of upper-gripping jaws, a lever mounted for swinging 65

movement widthwise of the last and connected to one of the pair of jaws, a second lever fulcrumed on said first lever for swinging movement widthwise of the last to operate the other

- 5 jaw to grip the upper, a member connected to said second lever for thus swinging it, a spring tending to swing the second lever outwardly from the last about its connection with said member and thus also to swing the first lever outwardly 10 through the fulcrum connection between the levers, and means for limiting such outward movements of the two levers.

73. In a machine for shaping uppers over lasts, the combination with upper-shaping means comprising

- 15 wipers movable to wipe the marginal portion of an upper inwardly at the opposite sides of the forepart of a last, of grippers constructed and arranged to grip the marginal portion of the upper outspread over the wipers at the opposite 20 sides of the forepart and movable inwardly toward the last in response to the pull of the upper thereon in the upper-shaping operation, each of said grippers comprising a pair of upper-gripping jaws, a lever mounted for swinging movement 25 widthwise of the last and connected to one of the pair of jaws, a second lever supported on said first lever for swinging movement widthwise of the last to operate the other jaw to grip the upper, a yieldable fulcrum connection between the two 30 levers affording provision for such swinging movement of the second lever, a member connected to the second lever for thus swinging it to effect the gripping of the upper and for further swinging it thereafter against the resistance 35 of said yieldable fulcrum connection, and a spring tending to swing the second lever outwardly from the last about its connection with said member and thus also to swing the first lever outwardly 40 through said fulcrum connection between the levers prior to the gripping of the upper and through the gripper jaws after the gripping of the upper.

74. In a machine for shaping uppers over lasts, a device for clamping an upper against a last

- 45 around the forepart exteriorly of the last bottom, said device comprising a plurality of interconnected links arranged to extend in a series around the forepart of the last and rearwardly and inwardly beyond the ball line for pressing the upper inwardly against the last, and means connected to the rearmost links of the series for forcing said rearmost links inwardly toward the sides of the last and also lengthwise of the last for pulling the other links inwardly toward the last 50 55 through their connections with said rearmost links, the rearmost links being curved to conform substantially to the contour of the sides of the shoe at the rear of the ball line.

75. In a machine for shaping uppers over lasts, a device for clamping an upper against a last

- 60 around the forepart exteriorly of the last bottom, said device comprising a plurality of interconnected links arranged to extend in a series around the forepart of the last and rearwardly and inwardly beyond the ball line for pressing the upper inwardly against the last, and operating means 65 comprising toggles connected to the rearmost links of the series for forcing them inwardly toward the sides of the last and also lengthwise of the last for pulling the other links inwardly toward the last through their connections with said rearmost links.

76. In a machine for shaping uppers over lasts, a device for clamping an upper against a last

- 75 around the forepart exteriorly of the last bot-

tom, said device comprising a pair of links constructed and arranged to extend around the toe end of the last and mounted for swinging movements relatively to each other, a pair of links pivotally connected to said end links and arranged to extend along the sides of the forepart approximately to the ball line, and other links pivotally connected to said last-named links and arranged to extend inwardly along the sides of the last at the rear of the ball line, and means connected 10 to said inwardly extending links for forcing them inwardly toward the sides of the last and also lengthwise of the last for pulling the other links also inwardly toward the last.

77. In a machine for shaping uppers over lasts, a device for clamping an upper around an end of a last exteriorly of the last bottom, said device comprising a pair of links constructed and arranged to extend around the end face of the last and mounted for swinging movements each about 20 a fixed axis at the end of the last, other links connected to said end links and arranged to extend along the sides of the last, and means connected to said other links for forcing them inwardly toward the last and also lengthwise of the last to 25 cause them to pull the end links inwardly.

78. In a machine for shaping uppers over lasts, a device for clamping an upper around the forepart of a last exteriorly of the last bottom, said device comprising a plurality of interconnected 30 links arranged to extend in a series about the forepart of the last and rearwardly and inwardly beyond the ball line and including a pair of links arranged to extend around the end of the toe and each mounted to swing about a fixed axis at the 35 end of the toe, and means connected to the rearmost links of the series for forcing them inwardly toward the sides of the last and also lengthwise of the last to cause them to pull the other links inwardly toward the last.

79. In a machine for shaping uppers over lasts, a device for clamping an upper around the forepart of a last exteriorly of the last bottom, said device comprising a plurality of interconnected links arranged to extend in a series about the 45 forepart of the last and rearwardly and inwardly beyond the ball line and including a pair of links arranged to extend around the end of the toe and each mounted to swing about a fixed axis at the end of the toe, and operating means comprising 50 toggles connected to the rearmost links of the series for forcing them inwardly toward the sides of the last and also lengthwise of the last to cause them to pull the other links inwardly toward the last.

80. In a machine for shaping shoe uppers, the combination with upper-shaping means, of upper-positioning means constructed and arranged to abut against the rear edge of the toe cap of an upper at the opposite side margins of the upper, 60 upon relative movement of said positioning means and the upper in a direction lengthwise of the upper, to position the upper in proper relation to said upper-shaping means prior to the upper-shaping operation.

81. In a machine for shaping shoe uppers, the combination with upper-shaping means, of upper-positioning means constructed and arranged to abut against the rear edge of the toe cap of an upper, upon relative movement of said positioning means and the upper in a direction lengthwise of the upper, to position the upper in proper relation to said upper-shaping means prior to the upper-shaping operation, and means for pressing the upper yieldingly against said posi- 70 75

tioning means during such relative positioning movement.

82. In a machine for shaping shoe uppers, the combination with upper-shaping means arranged 5 to receive the toe portion of an upper presented in an outspread condition, of devices constructed and arranged to abut against the rear edge of the toe cap of the upper at the opposite side margins of the upper, upon movement of the upper 10 per lengthwise by the operator with its toe portion in said outspread condition, to position the upper in proper relation to said upper-shaping means.

83. In a machine for shaping shoe uppers, the 15 combination with upper-shaping means arranged to receive the toe portion of an upper presented in an outspread condition, of devices constructed and arranged to abut against the rear edge of the toe cap of the upper at the opposite side portions 20 of the upper, upon movement of the upper lengthwise by the operator with its toe portion in said outspread condition, to position the upper in proper relation to said upper-shaping means, and means arranged to clamp the upper yieldingly on 25 said devices and movable away from said devices to receive the upper.

84. In a machine for shaping shoe uppers, the 30 combination with toe-embracing wipers arranged to receive the marginal portion of the toe end of an upper outspread along their outer faces, of devices located opposite said outer faces of the wipers and constructed and arranged to abut 35 against the rear edge of the toe cap of the upper to position the upper in proper relation to the wipers.

85. In a machine for shaping shoe uppers, the

combination with toe-embracing wipers operatively movable in wiping contact with an upper and arranged to receive the marginal portion of the toe end of the upper outspread along their outer faces, of devices movable with said wipers and arranged to gage the position of the upper relatively to the wipers when the wipers are in their starting positions.

86. In a machine for shaping shoe uppers, the 10 combination with toe-embracing wipers operatively movable in wiping contact with an upper and arranged to receive the marginal portion of the toe end of the upper outspread along their outer faces, of devices movable with the wipers and constructed and arranged to abut against 15 the rear edge of the toe cap of the upper, upon movement of the upper lengthwise by the operator, to position the upper in proper relation to the wipers when the wipers are in their starting 20 positions.

87. In a machine for shaping shoe uppers, the combination with toe-embracing wipers operatively movable in wiping contact with an upper and arranged to receive the marginal portion of the toe end of the upper outspread along their 25 outer faces, of devices movable with the wipers and constructed and arranged to abut against the rear edge of the toe cap of the upper, upon movement of the upper lengthwise by the operator, to position the upper in proper relation to the wipers when the wipers are in their starting 30 positions, and members relatively to which the wipers are movable arranged to clamp the upper yieldingly on said devices.

ARTHUR BATES. 35
